Owen, Owen & Crompton.

UNITED STATES PATENT OFFICE.

CHARLES W. GREENE, OF TOLEDO, OHIO, ASSIGNOR TO THE BOWLING GREEN RUBBER COMPANY, OF TOLEDO, OHIO, A CORPORATION OF OHIO.

DESIGN FOR A TIRE.

53,709.

Specification for Design.

Patented Aug. 19, 1919.

Application filed May 15, 1919. Serial No. 297,410. Term of patent 14 years.

To all whom it may concern:

Be it known that I, CHARLES W. GREENE, a citizen of the United States, residing at Toledo, in the county of Lucas and State of Ohio, have invented a new, original, and ornamental Design for Tires, of which the following is a specification, reference being had to the accompanying drawing, forming a part thereof.

Figure 1 is a broken view of a tire showing my design, and

Fig. 2 is a sectional view of the tire illustrated in Fig. 1 taken on the line 2, 2 indicated in Fig. 1.

I claim:—

The ornamental design for a tire as shown.

CHARLES W. GREENE.
